UNITED STATES PATENT OFFICE.

EMIL MADISON, OF MARINERS HARBOR, NEW YORK.

COIN-OPERATED DOOR-LOCK.

1,100,593.

Specification of Letters Patent. Patented June 16, 1914.

Application filed November 1, 1913. Serial No. 798,736.

To all whom it may concern:

Be it known that I, EMIL MADISON, a citizen of the United States, residing at Mariners Harbor, Staten Island, in the county of Richmond and State of New York, have invented new and useful Improvements in Coin-Operated Door-Locks, of which the following is a specification.

The general objects of this invention are to obviate the necessity of having key-attendants for private or pay toilets, lavatories and the like, in public places such as railroad terminals, and similar structures, and to expedite the admittance into such pay toilets, and lavatories upon the depositing of a pre-determined denomination of coin or check. And to these ends the invention consists of a coin or check-controlled lock mechanism adapted to be positioned on the door of a compartment and having means interlocking with the sash of the door, adapted to be released upon the insertion of a coin or check in the said lock mechanism.

Other objects will appear and be better understood from that embodiment of my invention of which the following is a specification, reference being had to the accompanying drawings forming part hereof, in which:

Figure 1 is a front elevational view of a door showing the exposed portion of my invention applied thereto. Fig. 2 is a rear elevational view of the lock having the back portion of the casing removed so as to show the inclosed mechanism. Fig. 3 is a horizontal cross sectional view taken on the line 3-3 in Fig. 2. Fig. 4 is an enlarged detailed front elevational view of the indicator. Fig. 5 is a horizontal cross sectional view taken on the line 5-5 in Fig. 4. Fig. 6 is a vertical cross-sectional view taken on the line 6-6 in Fig. 2. Fig. 7 is a perspective view of a portion of the door sash showing a portion of the lock mechanism thereon.

The lock *a* may be positioned at any convenient location on the door *b*, but it is preferred to be within easy reach of an operator, as shown in Fig. 1.

When the door is locked as shown in Fig. 2, the bolt *5* is engaged with the keeper *6* mounted in the sash of the door *c*. This bolt operates in a casing or housing *7*, in which is positioned a spring *8*, for pressing the bolt outwardly. This spring surrounds

a rod *9*, that projects beyond the casing and is loosely connected to a rock-arm *10* adapted to be swung on the pivot *11*, and provided at its lower end with a toe *12*. A second rock-arm *13* is pivoted at *14*, and is provided with a toe *15* at the lower end. A lug *16* prevents the backward movement of the toe portion, which backward movement is caused by the leaf-spring *17* pressing forwardly the upper portion of the rock arm *13*.

Mounted at the upper portion of the rock arm *13* is a knob or handle *18*, that projects out on the face of the door, and which travels in a guide slot *19*. A chute *20*, opening in the face plate *21* on the door, communicates with the interior of the casing *22* which surrounds the mechanism, and as the coin *d* is dropped into the chute from the front of the door, it will fall into engagement with the toes *12* and *14*, and be held thereinbetween, as shown in Figs. 2 and 6.

A tongue *23* is slidably fitted in the casing *24* and is provided with an extending rod *25*, which operates in a collar *26*. This collar acts as a stop for the spring *27* which surrounds the rod, and which is compressed when the tongue *23* is retracted, as shown in Fig. 2.

Connecting the toe portion of the arm *10* with the rod *25* is a link *28*, shown in the drawing in the form of a spring. Upon the door *b* being closed the tongue contacts with the plate *29*, mounted on the sash of the door, and the tongue is forced to the retracted position. Obviously, upon the door being opened the tongue freed from the plate *29*, is forced outwardly by the spring *27*; this action is sufficiently strong to draw back the toe *12* of the arm *10* and widen the space between the toes *12* and *14*, whereupon the captured coin *d* will drop into the money cup *30*; this cup is provided with a hinge or hasp portion *31*, which is adapted to be secured to the casing *22* by the co-operation of the staple *32* and the lock *33*. The portion *34* of the casing *22* is adapted to be slidably fitted to the said casing as it is desirable to have access to the coin-engaging mechanism when such is necessary; and the lower part of such portion *34* is constructed so as to be detachably secured to the money-cup *30*.

Positioned in the lock is a rod *35*, which operates in a guide *36*, and is pivotally connected to a lever *37*. A spring *38* surrounds the rod and is so connected to the rod and

guide that upon the rod 35 being retracted, the spring is tensioned or stretched and operates to project the rod outwardly, when permitted. Similar to the operation of the 5 above described tongue 23, the rod 35 is normally disposed outwardly and is forced into the retracted position shown in Fig. 2, by the plate 39 carried by the door sash c. This rod operates the indicating mechanism 10 e and when retracted, causes the said mechanism to assume the position shown in Fig. 2. The lever 37 is pivoted at 40 and is connected at the lower end to a rack 41, which engages with and operates a toothed wheel 15 42. This rack is kept into engagement with the wheel by the operation of a leaf-spring 43 which is carried by the plate 44. The wheel carries a dial 45, which is protected by a casing 46 mounted on the face of the 20 door. This casing is provided with a recess 47, which permits the exposition of a predetermined legend, as the wheel is operated by consecutive openings of the door; in order that the wheel may be rotated in one 25 direction only, a pawl 48 is carried by the wheel and is positioned to engage with a ratchet 49 mounted on the shaft of the wheel.

In the drawings the mechanism is shown in the locked position, as when the compartment is unoccupied. The rod 35 upon being retracted, causes the dial 45 to expose "Vacant" and the tongue 23 being retracted allows the toe portion to go forwardly; the spring 8 manifestly projects the bolt 5 into 35 engagement with the keeper 6 in the sash.

To operate, the prospective occupant of the compartment inserts a predetermined required coin, and as the coin falls into engagement with the toes of the rock arms 10 40 and 13, the operator moves laterally the handle or knob 18. This swings the rock arm 13 and pushes the toe 15 forwardly; which action, through means of the inter-position of the coin, pushes the toe 12 backwardly, 45 thus swinging the rock-arm. As the upper-

portion of the arm moves forwardly, the lock-bolt 5 is retracted and the door is in position to be opened. Upon the door being opened, the spring 27, as above described, projects the tongue 23, allowing 50 thereby the release of the coin, which falls into the money-depository. Simultaneously with the opening of the door the spring 38 is permitted to project the rod 35 outwardly, which, through the lever 37, pushes forwardly the rack 41, but by virtue of the pawl engaging with the ratchet the wheel is rotated and turns the dial so that "Occupied" is exposed. As the door is closed, the tongue 23 is cammed inwardly by the plate 60 29, and similarly the rod 35 is retracted. But it will be seen that as the rod moves inwardly and retracts the rack bar, the wheel is rotated independently of the dial, as the pawl carried by the wheel, slides over and 65 does not engage with the teeth of the ratchet. Obviously, the dial is operated only upon the opening of the door, and upon the occupant of the compartment vacating, the door is opened and the dial exposes the 70 third quarter thereof marked "Vacant".

What is claimed as new is:

A lock comprising a casing having a coin slot, a rock arm pivoted in the casing adjacent the slot, a bolt operatively connected 75 with one end of the rock arm, a spring pressed tongue operatively connected with the other end of the rock arm and having an end portion projecting beyond the edge of the casing, and means movably mounted for 80 holding a coin against the rock arm whereby the said means and the said rock arm may be moved simultaneously to retract the bolt.

In testimony whereof I affix my signature 85 in presence of two witnesses.

EMIL MADISON.
